Max Berger.

UNITED STATES PATENT OFFICE

MAX BERGER, OF JENA, GERMANY, ASSIGNOR TO THE FIRM CARL ZEISS, OF JENA,
GERMANY

MICROSCOPE STAND

Application filed November 25, 1930, Serial No. 497,978, and in Germany December 4, 1929.

I have filed an application in Germany, December 4, 1929, of which the following is a specification.

The great majority of microscopes are finely focused by a pinion head which is disposed at the upper part of the stand at the same height as the tube. However, use is made also of another type of microscopes, which have their pinion head at the lower part of the stand and, therefore, are completely different in construction not only as regards the focusing device but also as regards the stand.

The present invention applies to microscopes that have a lower pinion head and are finely focused by means of the well-known device in which the tube is supported by a lever that, being actuated by a gearing, for instance a toothed-wheel gearing, imparts it a slow motion, and aims at providing this lever in the upper part of the stand, while the gearing is disposed in the lower part of the stand. Notwithstanding the fact that the pinion head for fine focusing is provided below and that for better convenience its axis is even made to coincide with the tilting axis of the microscope stand, this arrangement permits of giving the stand its usual form again, which, compared with the construction of the hitherto known microscopes of this type, not only provides a considerable economical advantage but also allows of overcoming the disadvantages regarding focusing accuracy inherent in the said kind of microscopes.

A specially suitable device is obtained when the lever that is disposed in the upper part of the stand and supports the tube is coupled by a push-rod to the gearing.

The accompanying drawing shows a constructional example of the object of the invention partially in a section and partially in elevation.

The stand represented in the drawing consists of a base plate *a* on which a hollow pillar bracket *b* is so mounted as to allow of being tilted on an axis *A*. The pillar bracket *b* supports a tube *c* which, together with a slide *c'* whereon it is coarsely adjustable by means of a head *c''*, rests on a lever *d* onto

which it is pressed by its own weight as well as by a spring *e*. In the lower part of the pillar bracket *b* is a toothed-wheel gearing which reduces the speed of the turning movement of a head *f* whose turning axis coincides with the tilting axis *A* of the pillar *b*. The toothed-wheel gearing consists of a pinion *g* which is fixed to the axle of the head *f* and meshes with a toothed-wheel *g'*, and of a pinion *g''* which is fast with the axle of the toothed wheel *g'* and meshes with teeth *h'* of a lever *h*. This lever *h* turns about an axis *B* and is jointed at its free end to a push-rod *i* which is connected also with the lever *d*.

As can be deduced from the foregoing, a turning movement of the milled head *f* causes the tube to be slowly raised or lowered according to the direction in which the head *f* is turned.

I claim:

1. On a microscope stand a carrier adapted to hold a microscope tube and being movably mounted on the stand, a lever mounted in the upper part of the stand and acting on the carrier, a pinion head disposed at the lower part of the stand, a gearing being situated in the lower part of the stand and coupled to the pinion head, and a push-rod connecting this gearing with the said lever.

2. On a microscope stand a base, a hollow pillar bracket tiltably mounted on the base, a carrier adapted to hold a microscope tube and being movably mounted on the pillar bracket, a lever provided in the upper part of the pillar bracket and acting on the carrier, a pinion head disposed at the lower part of the stand, a gearing being situated in the lower part of the pillar bracket, the axis of the pinion head coinciding with the tilting axis of the pillar bracket, a gearing being disposed in the lower part of the pillar bracket and coupled to the pinion head, and a push-rod connecting this gearing with the said lever.

MAX BERGER. 95
